UNITED STATES PATENT OFFICE.

OLIVIER PIETTE, OF PARIS, FRANCE, ASSIGNOR TO SOCIÉTÉ ANONYME DES FOURS À COKE SEMET-SOLVAY & PIETTE, A CORPORATION OF BELGIUM.

HORIZONTAL COKING-OVEN.

1,378,129.

Specification of Letters Patent. Patented May 17, 1921.

Application filed January 28, 1918. Serial No. 214,160.

To all whom it may concern:

Be it known that I, OLIVIER PIETTE, a citizen of Belgium, temporarily residing in Paris, France, have invented certain new and useful Improvements in Horizontal Coking-Ovens, of which the following is a specification.

The present invention relates to improvements in horizontal coking retorts having vertical channels or flues and means for the recuperation of the heat and by-products and the primary object is to modify ovens of the type hitherto known for the purpose of rendering it possible to heat same with producer gas, this gas as well as the air necessary for combustion being previously heated by means of the heat carried by the fumes, said heat, according to the present invention, being recuperated where the fumes discharge from the heating channels of the oven proper.

The said recuperation of heat is effected by suitable devices provided in the foundations of the oven without the course of the gases, or of the air or fumes being reversed or inverted.

The accompanying drawings show by way of example one embodiment of an improved coking oven according to the invention and in said drawings—

Figure 1 is a vertical transverse section through an oven comprising two parts, the left-hand portion being a section on the line A—B of Fig. 2 and the right-hand portion a section on the line C—D of said figure.

Fig. 2 is a cross section of Fig. 1; and Fig. 3 is an enlarged detail section illustrating the vertical and horizontal channels included in my invention.

Each oven is transversely divided into two substantially symmetrical parts entirely independent of one another with regard to their heating. Beneath the sole flue of each retort and in alignment with same is a chamber divided into a pair by a partition wall located on the battery center line. In alternate pairs of chambers are located the recuperators A' and G for air and producer gas respectively.

The gas is led under the gas-recuperators

G by means of three ducts 18, 19 and 20 each provided with a regulating valve, said ducts distributing the gas into three chambers each of which feeds a certain number of channels α in the recuperator extending upwardly between adjacent horizontal channels b in registry with suitable apertures in the baffles 11 as shown in detail in Fig. 3. The air is admitted below the air recuperators A' and can also be distributed into several chambers each feeding a certain number of rising channels α in which the air is heated.

The air entering through aperture 1 first rises in the ascending channels α in a zig-zag course (which, obviously, is longer than the vertical dimension of the chamber A') and thence passes through the uptakes 2 to the burners 3 where it meets the gas which is fed through the tubes T and ducts 17 and which passes upwardly through the rising channels α and registering apertures of the baffles of the gas recuperators G, where it is heated. The gas passes through the uptakes 21 and orifices 4 terminating close to the burners. The gas is thus caused to mix with the air and ignites and the products of combustion rise in the channels 5 and pass thence to the horizontal flues 6 from which they pass downward into the two channels 7 (Fig. 1). These waste gases then pass through the right hand portion of Fig. 1 in the same manner as indicated in the section constituting the left side of Fig. 1, to wit, through the apertures 8 into the sole plate flue 9 then through chamber 10 from which they enter the horizontal channels b (which, obviously, are longer than the horizontal dimension of chamber G) of the upper portion of the recuperators. From the latter the said products pass through the chamber 12 and around the end of a baffle 11 and thus enter the channels b of the second portion of the said recuperators and so on until they reach the outlet duct 16 and the collecting flue F which leads them to the chimney. The horizontal channels b are arranged in groups between the baffles 11. As shown diagrammatically in Figs. 1 and 2 the

groups become progressively smaller from the top downwardly whereby the efficiency of the products of combustion as a heating medium is preserved until the duct 16 is 5 reached.

With the arrangement shown and described it is thus possible to heat the oven with producer gas without reversing the course of the gases or of the air or products 10 of combustion or waste gases by preheating both the gas and air for combustion while recuperating the heat of the waste gases at their discharge from the heating channels.

Burners B' are furnished with gas from a 15 pipe extending along the face of the battery and connected with the coke oven gas supply. Owing to the burners B' provided between the uptakes for the producer gas and air it is possible to make up any deficiency 20 of the producer gas by adding the requisite quantity of coking oven gas or even to heat the oven exclusively by means of coking oven gas, the producer gas recuperators being in this case employed for heating the air. 25 What I claim as my invention and desire to secure by Letters Patent of the United States is:—

1. A horizontal coke oven comprising alternating retorts and sets of heating flues, 30 chambers and ducts for introducing air to the heating flues, chambers and ducts for introducing producer gas to the heating flues, one of said chambers being located beneath one of said retorts and the other beneath 35 the next adjacent retort, the ducts from each chamber leading to two heating flues located on opposite sides of one of the retorts, a passage for the waste products from each set of heating flues through each of said chambers and forming in said chambers channels for the passage of air and producer gas in alternate chambers, the dimensions of the last named channels and passage being, within the chamber, respectively one several 40 times that of the horizontal dimension of the chamber and the other materially longer than the vertical dimension of said chamber whereby substantially all of the effective heat carried by the waste products is abstracted therefrom by recuperation and transmitted to the gas and air used for combustion, all of said gases traveling at all times in the same direction without reversal of their course. 45

2. A horizontal coke oven comprising alternating retorts and sets of heating flues, chambers and ducts for introducing air to the heating flues, chambers and ducts for introducing producer gas to the heating flues, 50 one of said chambers being located beneath one of said retorts and the other beneath the next adjacent retort, the ducts from each chamber leading to two heating flues located

on opposite sides of one of the retorts, a passage for the waste products from each 55 set of heating flues to the axis of the oven, thence through the sole of each retort above the chambers to the outer end of the oven and then through each of said chambers and forming in said chambers channels for the 60 passage of air and producer gas in alternate chambers, the dimensions of the last named channels and passage being, within the chamber, respectively one several times that of the horizontal dimension of the chamber 65 and the other materially longer than the vertical dimension of said chamber whereby substantially all of the effective heat carried by the waste products is abstracted therefrom by recuperation and transmitted to the 70 gas and air used for combustion, all of said gases traveling at all times in the same direction without reversal of their course.

3. A horizontal coke oven comprising heating means, channels for conducting air, 75 channels for conducting producer gas to said heating means, groups of recuperating channels extending transversely to the direction of said conducting channels, said groups becoming progressively smaller in a downward 80 direction and means whereby the products of combustion are conducted to the uppermost group of recuperating channels, said products of combustion passing successively through successive groups of recuperating 85 channels to preheat the air and gas as they pass through said conducting channels to said heating means.

4. A horizontal coke oven comprising heating means, channels for conducting air, 90 channels for conducting producer gas to said heating means, recuperating channels extending transversely to the direction of said conducting channels, burners located 95 between the gas and air channels whereby coke oven gas may be used as a substitute for or supplemental to the mixture of air and producer gas to heat the heating means, and means whereby the products of combustion are caused to pass through said recuperating channels to preheat said air and producer gas as they pass through said conducting channels to said heating means.

5. A horizontal coke oven comprising heating means, a plurality of apertured baffles located beneath said heating means and forming a series of superimposed chambers communicating with each other, groups of horizontal channeled member in said chambers constituting recuperating channels, said 115 groups of channeled members being spaced apart and having an exterior contour whereby vertical undulating channels are formed in registry with the apertures in said baffles and communicating with said heating 120 means, means whereby air on the one hand

and producer gas on the other are conducted to and caused to pass through said undulating channels to said heating means and means whereby the products of combustion 5 are conducted from said heating means to the first group of recuperating channels, said products of combustion passing successively through successive groups of recuperating channels from one chamber to

another to preheat the air and producer gas 10 prior to their arrival at said heating means.

In witness whereof I have signed this specification in the presence of two witnesses

OLIVIER PIETTE.
